PERCUSSION FUSE

Marc Birkigt, Bois-Colombes, France

Application March 27, 1936, Serial No. 71,326
In Belgium January 17, 1936

6 Claims. (Cl. 102—39)

The present invention relates to percussion fuses for projectiles rotating about their axis along their trajectory and it concerns, especially although not exclusively, fuses for small caliber shells.

The object of the present invention is to provide a fuse of this type which is better adapted to meet the requirements of practice than fuses for the same purpose made up to the present time.

According to the present invention, I make use of balls or the like for locking the striker or firing pin as long as it is necessary, that is during handling of the projectile and before it is fired from the gun, and I devise the parts in such manner that, when the projectile is rotating about its axis, these locking balls are slidably held for a certain length of time between two parts which move relative to each other, while the balls move away from the axis of revolution of the projectile, for releasing the striker or firing pin.

Other features of the present invention will result from the following detailed description of specific embodiments thereof.

Preferred embodiments of the present invention will be hereinafter described, with reference to the accompanying drawings, given merely by way of example, and in which:

Fig. 1 is an axial sectional view of a percussion fuse made according to a first embodiment of the present invention;

Figs. 2, 3 and 4 are views, similar to Fig. 1, illustrating different characteristic positions of the parts of the fuse, in the course of the operation thereof;

Fig. 5 is an end view of one of the elements of said fuse;

Fig. 6 is a partial sectional view, similar to Fig. 1, showing a modification;

Fig. 7 is an axial sectional view of a percussion fuse made according to another embodiment of the present invention;

Figs. 8, 9, and 10, similar to Fig. 7, illustrate different characteristic positions of the parts of the fuse shown in said Fig. 7, corresponding to different characteristic relative positions of the parts of said fuse in the course of the operation thereof;

The embodiments described by way of example describe percussion fuses for projectiles to be fired in guns provided with riflings.

In order to lock the firing pin which is carried by the fuse, as long as necessary to obtain a safety period, I provide a system of balls capa-

ble, as long as they are kept close to the center line of the fuse, to bear rearwardly against a fixed stop element and to form stops for an enlarged portion of the firing pin or striker, so as to prevent the latter from coming into contact with the detonator of the fuse.

The fuse body consists of a hollow metallic piece 1 which extends rearwardly, in the usual manner, so as to form a chamber 2 containing detonator 3 and priming charge 4. This chamber is closed by a fixed piece 5 in the central part of which there is provided a hole 6 through which the firing pin 7 is slidably guided.

The front part of said body 1 is then hollowed out in such manner as to form therein a chamber 8 having, at the front part thereof, an axial bore 9 closed at its front end by a small disc 10.

Firing pin or striker 7 includes, on the one hand, a head 11 capable of sliding in bore 9, and on the other hand an enlarged part 12, located for instance at the middle part of said firing pin, this enlarged part being adapted to form the front stop for the locking balls 13.

I further provide, in chamber 2, an element capable of acting as a rear stop for said balls, 25 said element consisting, for instance, of a cylindrical sleeve 14 carried by piece 5.

The fuse body being thus constituted, I provide means whereby balls 13 are held between two parts which move away from each other when the projectile is rotating after being fired, while the balls themselves move away from the axis of rotation under the effect of the centrifugal force, so as to release the striker or firing pin by moving out of the way of said enlarged portion 35 of the firing pin.

Such an arrangement may be made in different manners but the embodiment shown by the drawings is believed to be the most advantageous.

As shown by way of example by Figs. 1 to 4, there is provided in chamber 8, behind bore 9, a longitudinal housing 15, for instance of cylindrical shape, which may extend rearwardly as far as sleeve 14.

Inside this housing 15, a ring-shaped member 16 is securely, but elastically, held in said housing. For instance, as shown by the drawings (Fig. 5) this ring-shaped member 16 is slit and given a size such that it must be contracted for inserting it into housing 15, so that ring-shaped member 16 is securely held in position by friction as long as it is not subjected to the action of an extremely high force, such as that exerted thereon, in a rearward direction, when the cartridge is fired.

This ring-shaped member 16 is made of such a height and a thickness such that, on the one hand, when it occupies its front position (Fig. 1), in which it is set when the parts are assembled, its 5 rear end is located opposite balls 13 when the latter are located between sleeve 14 and the enlarged part 12 of the firing pin, thus keeping said balls in the locking position. On the other hand, when said member 16 is in its rear position (Figs. 10 2 to 4), which occupies after the cartridge has been fired, the front part of said member 16 is located opposite balls 13.

The inner face of this front part of member 16 is of flaring shape toward the front, forming 15 a cone of an angle of for example 30°, said conically-shaped part being advantageously of a length such that, when ring-shaped member 16 is in its rear position, balls 13 are located opposite said conical part of member 16.

20 The firing pin and its enlarged part 12 are arranged in such manner that, when, under the effect of the centrifugal force, balls 13 move forward into said conical portion 17, they push said firing pin gradually toward the front until they 25 are capable of moving past enlarged portion 12, thus releasing the firing pin.

For this purpose, for instance, the rear face of the enlarged part 12 of said firing pin is given 30 the shape of a cone 18 the apical angle of which is greater than that of conical part 17, for instance 50°.

Supposing now that all the parts of the fuse above described are assembled as shown by Fig. 35 1, in which the striker or firing pin is locked, this fuse works in the following manner:

When the shot is fired, ring-shaped member 16 is moved rearwardly (Fig. 2), the enormous acceleration of the shell in the bore of the gun keeping the balls applied against sleeve 14 and the 40 firing pin applied against the balls.

When the acceleration ceases, that is to say after the shell has left the gun, the balls are gradually caused to rotate, rolling at a higher and higher rate inside part 17 and pushing firing 45 pin 17 forwardly.

Finally, said firing pin is released when the balls have moved past the edge of enlarged portion 12.

It will be readily understood that the safety 50 period elapsing after the shell has left the gun depends upon the time during which the firing pin is moving forwardly under the effect of the thrust of the balls and also upon the retardation 55 of the movement of the shell along its path of travel.

In order to obtain this period of any desired length, I may, for instance, provide balls of a size and weight depending on the length of such period. The apical angles, the axial length and 60 relative thickness of conical portions 17 and 18 may also be made of various sizes to affect the length of the safety periods.

I may also, in order to increase safety, provide 65 means for retarding the forward movement of the striker or firing pin.

For instance I could arrange the head 11 of the striker or firing pin and bore 9 as an air brake or dash-pot.

I may also provide for a certain friction be- 70 tween head 11 and bore 9, for instance by means of an elastic annular member 19 (Fig. 6) carried by the front part of said head and adapted to slide frictionally along the wall of said bore.

I may also, still for the same purpose, vary the 75 size and weight of the striker, for example, for

increasing or reducing the friction between pin 7 and the wall of hole 6.

Advantageously, according to the present invention, said striker is made of two parts, that is, a steel body carrying the portion 12 of enlarged section and a head portion of light metal, for instance fixed to said body through securing means 20 which can be opened if, for some accidental reason, the head of the firing pin undergoes a shock during handling. 10

For this purpose, the front face of enlarged portion 12 is made of frusto-conical shape and it carries a projection 21 the base of which is provided with a groove in which is fixed the base of a tubular element of relatively small thickness 15 which carries head 11.

According to another embodiment of the invention, illustrated by Figs. 7 to 10, the fuse is similar to that above described but, instead of a single ring-shaped element 16 it includes two 20 ring-shaped members 22 and 23. Element 22, located at the rear part of the device is fitted with considerable friction inside housing 15 and it serves to lock the parts in inoperative position. The other ring-shaped member 23 is adapted to 25 slide freely inside said housing and serves to keep the balls in locking position after the shot has been fired until the projectile reaches the desired point of its trajectory.

This type of fuse was described in applicant's 30 prior patents.

Ring-shaped member 23 is provided, at the rear part thereof, with a bevel 24 arranged in such manner that its forward edge is located opposite the balls when, after the shot has been 35 fired, ring-shaped members 22 and 23 have moved simultaneously in a rearward direction. This position is shown by Fig. 8.

While in prior devices, the forward movement of ring-shaped member 23 took place only as a 40 result of the retardation of the motion of the projectile along its trajectory, in the present fuse, this movement is further increased by the thrust of the balls on bevel-shaped part 24, as said balls are being gradually placed in rotation 45 by the body of the fuse.

Anyway, when ring-shaped member 23 has been pushed in a forward direction a sufficient distance, balls 13 engage between the two ring-shaped members (Fig. 9) and release the striker 50 so that the latter, when the projectile meets an obstacle, is free to strike the detonator (Fig. 10).

In the general manner, while I have, in the above description, disclosed what I deem to be practical and efficient embodiments of the present invention, it should be well understood that I do not wish to be limited thereto as there might be changes made in the arrangement, disposition and form of the parts without departing from the principle of the present invention as contained 55 within the scope of the appended claims.

What I claim is:

1. A fuse for a projectile intended to move along its trajectory with a rotary movement about said trajectory which comprises, in combination, a fuse body, a detonator carried by said body, an axial striker movable in said body for action on said detonator, balls adapted to coact with said striker for locking it in a position out of contact with said detonator, means for keeping 65 said balls in the locking position thereof, adapted to be brought out of action by the acceleration undergone by the projectile when the latter is fired, and a member movable axially in said body 70 having a flaring surface adapted to cooperate 75

with said balls so as to permit outward motion thereof for releasing them from locking engagement with said striker when said member is moved axially by the axial component of the 5 thrust exerted, under the effect of the centrifugal force, by said balls on said member.

2. A fuse for a projectile intended to move along its trajectory with a movement of rotation about said trajectory which comprises, in combination, a fuse body with a cylindrical axial housing therein, a detonator carried by said body, a striker movable axially in said housing for action on said detonator, balls in said housing adapted to operatively engage said striker for locking it in a position out of contact with said detonator, a ring fitting with a high friction in said housing, the rear part of the inner surface of said ring being of cylindrical shape so as to normally keep said balls into engagement with 10 said striker and the front part of said inner surface being of frontwardly flaring shape, said ring being adapted to slide in said housing, under the effect of the acceleration undergone by said projectile when the shot is fired, into a position in 15 which said flaring surface cooperates with said balls, and a conical part rigid with said striker adapted to cooperate with said balls so as to transmit to the striker a frontward movement under the effect of the axial component of the 20 thrust exerted thereon, under the effect of the centrifugal force, by said balls running along said flaring inner surface of said ring, whereby said conical part is brought into a position in which it permits said balls to escape outwardly 25 into the peripheral part of said housing, between said conical part and the front edge of said ring.

3. A fuse according to claim 1 in which the means for keeping said balls in the locking position prior to the firing of the shot consist of a ring fitting with a high friction inside said body, and the member movable in said body consists of a ring having a bevelled inner surface movable freely inside said body.

4. A fuse for a projectile intended to move along its trajectory with a rotary movement around its axis, comprising in combination a fuse body, a detonator and a striker within said body, said striker and said detonator being movable

relative to each other for bringing said striker in contact with said detonator, means for normally preventing said movement, said means being movable within said fuse body toward the outside under the action of centrifugal force 5 when said projectile is rotating about its own axis, annular means surrounding said first means, said last means having at least one cylindrical and one conical inner wall and being movable axially within said fuse body, said last means being so positioned relative to said first means that said cylindrical wall is located opposite said first means before said projectile is fired, while said last means are moved by the inertia of firing into a position where said first means are surrounded by said conical wall, whereby said first means 10 are disengaged from locking position in which said relative movement was prevented by the centrifugal action of said first means upon said conical wall. 15

5. A fuse for a projectile according to claim 4, said annular means being frictionally secured in position and in contact with said first means before said projectile is fired.

6. A fuse for a projectile intended to move along its trajectory with a rotary movement around its axis, comprising in combination a fuse body, a detonator and a striker within said body, said striker and said detonator being movable relative to each other for bringing said 20 striker in contact with said detonator, means for normally preventing said movement, said means being movable within said fuse body toward the outside under the action of centrifugal force 25 when said projectile is rotating about its own axis, a support having a conical inner wall and being movable axially within said fuse body, means for holding said first means in the locking position thereof and said support out of contact 30 with said first means before said projectile is fired, while said last means are moved by the inertia of firing into a position where said first means are surrounded by said conical wall, whereby said first means are disengaged from 35 locking position in which said relative movement was prevented, by the centrifugal action of said 40 first means upon said conical wall. 45

MARC BIRKIGT.
